(57) **CLAIM**

The ornamental design for a fixing bracket of room mirror for a car, as shown.

DESCRIPTION

FIG. 1 is a front, right perspective view of the fixing bracket of room mirror for a car showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is bottom, left perspective view; and,

FIG. 9 is a view shown in use thereof.

The broken lines showing of the car window and room mirror represents the environment of the claimed design and forms no part thereof.

1 Claim, 4 Drawing Sheets
